ELECTRIC CIRCUIT BREAKERS

Edward Coleman, Walsall, England, assignor to J. A. Crabtree & Co. Limited, Walsall, England, a British company

Application April 18, 1956, Serial No. 579,020

Claims priority, application Great Britain June 17, 1955

5 Claims. (Cl. 200—94)

This invention relates to electric circuit breakers and is particularly concerned with lever-operated arrangements embodying a magnetic overload device. The object of the invention is to facilitate production assemblage and calibration.

According to this invention, plates for receiving pivot pins are riveted to a supporting frame and are formed with feet securable to a casing by screws. The improved arrangement enables the frame to be secured against undesired raising or lifting away from the fixed contacts, when the cover is removed to permit calibration, and avoids the necessity for employing a dummy cover for holding the parts in position during this factory operation.

Another important feature of the invention resides in securing one of the plates to the casing in the plane of the lever pivot. Disposing securing means in this plane excludes any possibility of the riveted inner unit inadvertently lifting away from the fixed contacts.

A further feature of the instant invention encompasses the use of flat plates adapted to be stamped out of a thin metal strip, thus eliminating undue wastage of material. The flat strip can then be accurately drilled for both pivot and rivet holes by a single tool at one operation for economical mass production.

In order to enable the invention to be readily understood reference will now be made to the accompanying drawings illustrating by way of example different constructions for carrying the invention into effect, in which drawings:

Figure 1 is a side elevation with parts in section of a double-pole earth leakage circuit breaker.

Figure 2 is a section on the line II—II of Figure 1.

Figure 3 is a perspective view of the lever, and an associated set of parts for one pole of the double-pole construction, such parts being disassembled from one another.

Figure 4 is a perspective view of one of the plates for a single pole construction.

Referring to Figures 1 to 3 of the drawings a pair of parallel metal plates 1 are disposed on the inner faces of the side walls 2 of the moulded casing 3. Each plate is formed with a bent foot 1^a having a tapped opening into which is entered a screw 4 introduced through a countersunk opening in the base of the moulded casing. Each of a pair of shorter parallel plates 5, disposed between the plates 1, is connected to one of the latter by a right-angled frame 6 secured by a screw 7 to the base. Short rectangular projections 8 on the sides of the frame are entered into similarly shaped openings 9 in each pair of plates 1 and 5, and are riveted over in an assembly jig. Another pair of slightly longer projections 8^a on the frame are employed for location in the moulded casing, one of these projections extending through an opening 9^a in the plate 1, into a groove 10 in a side wall of the casing, while the other projection is disposed in a groove 11 in a central partition 12.

The plates 1 are formed with circular holes for the reception of pins adapted for the mounting of different parts. Thus the pivot pin 13 for the lever 14 is mounted

2

in openings 15 at the upper ends of the plate 1, the outer ends of pins 13 extending into guiding grooves 16 in the moulded cover 17, see Fig. 2. A short inwardly extending rivet 18 on each plate 1 acts as a stop for one arm of a lever spring (not shown). Each plate 1 is also formed with a circular hole 19^a for receiving the reduced end of a pivot pin 19 on which an armature 20 is pivotally mounted. This end is riveted over for rigidly securing the pin 19 in position within the hole 19^a and serves also for securing a stop member 21 having an extension 21^a overhanging the armature for limiting the spring-urged movement of the armature away from its magnet 22. The stop 21 is also formed with a rectangular opening 21^b through which extends a projection 8^a. A spring 23 is coiled around the pin 19 and has an end engaging a depending trip leg 20^a of the armature. The free end of the spring legs being adapted to produce tripping by impinging on a transverse pin 30, see Fig. 1.

The operation of this device is similar to that described and disclosed in various patents to Wilckens, for example in Nos. 2,689,282; 2,690,486; and 2,781,433.

Pins 24 and 28 are received in holes 26 and 29 respectively in the lower ends of the plates 1 and 5. Each pin 24 serves for centering the convolutions 25 of a spring 25 the ends 25^a of which bear on the frame 6, while the loop 25^b acts on a moving contact 27 for urging it into pressure engagement with a fixed contact 31. Each moving contact 27 is formed with a short elongated slot 27^a, through which extends the pin 28, so that it is guided for pivotal movement to a restricted extent over such pin, this arrangement constituting the moving contact hinge or pivot.

For the single pole construction a lever actuates a single set of parts and the frame 6 is riveted to a plate 1 and to a plate 32, Figure 4, which is provided instead of the plate 5. The holes 33 and 34 in the plate 32 receive respectively the pins 13 and 19, the remaining holes therin corresponding to the similarly numbered openings in the plate 5, as shown in Figure 3.

The forms of the invention here described and illustrated are presented merely as examples of how the invention may be embodied and applied. Other forms, embodiments and applications of the invention, coming within the proper scope of the appended claims, will, of course, suggest themselves to those skilled in the art.

I claim:

1. In an electric circuit breaker having an insulated base, a fixed contact, a moving contact, a lever operating said moving contact, a toggle disposed between said lever and said moving contact, an electromagnet provided armature for tripping said toggle on overload, a frame having a right-angled foot for securing to said base, said frame provided with spaced projections thereon, pins disposed therein for pivotally mounting said lever, armature and moving contact; parallel plates lying entirely within one plane, said plates provided with perforations disposed in mutually spaced relationship therein constructed and arranged to mount said pins and receive said projections in registered alignment therewith, means for securing said frame and at least one of said plates in such mutually spaced alignment to said base, said aligned perforations serving to maintain said pivotal lever, armature and moving contact in operative registration.

2. In an electric circuit breaker having an insulated base, a fixed contact, a moving contact, a lever operating said moving contact, a toggle disposed between said lever and said moving contact, an electromagnet provided armature for tripping said toggle on overload, a frame provided with spaced rectangular projections thereon, pins disposed therein for pivotally mounting said lever, armature and moving contact; parallel plates lying entirely within one plane, said plates provided with perforations disposed in mutually spaced relationship therein con-

structed and arranged to mount said pins and matingly engage said rectangular projections in registered alignment therewith, means for securing said frame and at least one of said plates in such mutually spaced alignment to said base, said aligned perforations serving to maintain said pivotal lever, armature and moving contact in operative registration.

3. In an electric circuit breaker having an insulated base, a fixed contact, a moving contact, a lever operating said moving contact, a toggle disposed between said lever and said moving contact, a main spring, a moving contact hinge, an electromagnet provided armature for tripping said toggle on overload, a frame provided with spaced projections thereon, pins disposed therein for pivotally mounting said lever, armature and moving contact; parallel plates lying entirely within one plane, said plates provided with perforations disposed in mutually spaced relationship therein constructed and arranged to mount said pins and receive said projections in registered alignment therewith, means for securing said frame and at least one of said plates in such mutually spaced alignment to said base, said aligned perforations serving to maintain said pivotal lever, armature and moving contact in operative registration, wherein one of said plates engaging said frame is constructed and arranged to pivotally support said lever, armature, contact hinge and main spring.

4. An electric circuit breaker comprising an insulated base, a cover, a fixed contact, a moving contact, a lever operating said moving contact, a toggle disposed between said lever and said moving contact, an electromagnet provided armature for tripping said toggle on overload, pins for pivotally mounting said lever, armature and moving contact, a frame provided with spaced projections thereon, parallel plates lying entirely within one plane, said plates provided with perforations disposed in mutually spaced relationship therein constructed and arranged to

mount said pins and receive said projections in registered alignment therewith, means for securing said frame to said base, one of said plates being secured to said base in the pivotal plane of said lever serving to prevent separation from said fixed contact upon removal of said cover for calibration purposes, wherein said aligned perforations maintain said pivotal lever, armature and moving contact in operative registration.

5. An electric circuit breaker comprising an insulated base, a fixed contact, a moving contact, a lever operating said moving contact, a toggle disposed between said lever and said moving contact, an electromagnet provided armature for tripping said toggle on overload, pins for pivotally mounting said lever, armature and moving contact, a frame provided with spaced projections thereon, one of said projections extending for registered engagement with said base, parallel plates lying entirely within one plane, said plates provided with perforations disposed in mutually spaced relationship therein constructed and arranged to mount said pins and receive said projections in registered alignment therewith, means for securing said frame and at least one of said plates in such mutually spaced alignment to said base, said aligned perforations serving to maintain said pivotal lever, armature and moving contact in operative registration.
